[57] CLAIM

The ornamental design for a kitchen machine base unit, as shown and described.

DESCRIPTION

FIG. 1 is a front, top and right side perspective view of a kitchen machine base unit showing my new design, the unit being in open position;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of the kitchen machine base unit in the closed position with the motor block removed for ease of illustration;

FIG. 9 is a front elevational view of FIG. 8;

FIG. 10 is a rear elevational view of FIG. 8;

FIG. 11 is a top plan view of FIG. 8;

FIG. 12 is a bottom plan view of FIG. 8;

FIG. 13 is a right side elevational view of FIG. 8; and

FIG. 14 is a left side elevational view of FIG. 8.
